UNITED STATES PATENT OFFICE.

FRANK MUNSON WILCOX, OF LYME, CONNECTICUT.

POLE.

986,335.

Specification of Letters Patent.

Patented Mar. 7, 1911.

Application filed September 13, 1910. Serial No. 581,764.

To all whom it may concern:

Be it known that I, FRANK M. WILCOX, a citizen of the United States, and a resident of Lyme, in the county of New London and 5 State of Connecticut, have invented a new and Improved Pole, of which the following is a full, clear, and exact description.

An object of the invention is to provide a climbable pole for supporting wires, 10 clothes lines and the like.

For the purpose mentioned I provide a pole consisting of an elongated body, preferably hollow and constructed of iron, with means on the pole for climbing the same and 15 a flattened head formed on the pole for receiving the supports adapted to carry electric wires, clothes lines, and other current conducting or supporting devices.

Reference is to be had to the accompanying drawings, constituting a part of this specification, in which similar characters of reference denote corresponding parts in all the views, and in which—

Figure 1 is a side elevation of my invention; Fig. 2 is a fragmentary longitudinal section showing the interior construction; and Fig. 3 is a sectional plan view taken on the line 3—3 in Fig. 2.

Iron poles now generally employed for 30 the various purposes mentioned, are usually constructed of interlaced or connected girders and rods constituting a vertically extending lattice work. These poles, however, are clumsy in appearance and owing to their 35 open construction are exposed to all kinds of weather, which in time eats into the joints and weakens the pole considerably. Furthermore, poles constructed of lattice work, as mentioned, are generally of rectangular construction and receive a severe strain in heavy 40 gales and high winds.

In my device is embodied a round pole of 45 preferably tapering construction and having a hollow interior. The climbing supports are purposely made to protrude only a slight distance from the general line of the pole and thus a neat, strong, and serviceable pole is assured and the pole proper, being entirely

closed when in use, is substantially protected from any inclement weather and no moisture can penetrate into the interior of the pole. Furthermore, by providing a hollow pole, suitably insulated wires can be disposed inside the pole, especially in cases where it is desired to ground an electric 55 wire.

Referring more particularly to the drawings, I provide an elongated hollow body 10 adapted to be vertically supported in a preferably concrete base 11. The pole 10 is 60 provided with a flattened head 12 on which can be secured suitable cross supporting members 13 for carrying electric conductors and the like. A plurality of climbing supports 14 are arranged in a staggered fashion 65 on the body 10 and consist of an outwardly extended portion 15 and an upwardly extended portion 16, the said supports 14 being integrally formed on the outer peripheral surface of the pole and preferably in 70 two oppositely disposed vertical rows.

When a lineman or pole climber desires to climb the pole he places the spur of his climbers into the opening 17 formed by the portions 15 and 16, and after lifting himself 75 to the next support 14, repeats the operation at each successive support until he has climbed to the desired height on the pole. The climbing supports 14 are intentionally small in size, thus preserving the graceful 80 outline of the pole and also preventing any body from climbing the pole.

Having thus described my invention, I claim as new and desire to secure by Letters Patent:—

A pole comprising an elongated body and a plurality of laterally extended apertured climbing supports integrally formed on the said body.

In testimony whereof I have signed my 90 name to this specification in the presence of two subscribing witnesses.

FRANK MUNSON WILCOX.
